UNITED STATES PATENT OFFICE.

WILLIAM H. DANCE, OF CAMBRIDGE, MASSACHUSETTS.

DRIER FOR SAND, GRAVEL, ETC.

Application filed September 19, 1928. Serial No. 306,928.

This invention relates to a drier comprising an elongated open-ended drum mounted to rotate on an inclined axis, and provided with a series of longitudinally extending inwardly projecting flanges, known as fells, adapted to alternately raise and release loose material fed into the higher end of the drum, and a fixed hydrocarbon burner arranged to project flame into the lower end of the drum 10 toward the higher end, the material alternately raised and released in the drum being caused by the inclination and rotation of the drum to move in an approximately helical path from the higher to the lower end 15 and discharged at the latter, the material being dried by the heat generated by the burner. The vapor liberated from the material and the products of combustion escape from the higher end of the drum through a stack provided for that purpose.

It is very desirable in a drier of this character that the material being dried be prevented from dropping through and contacting with the burner flame, such contact causing the material to take up unconsumed oil.

The present invention has for its object to provide improved means for preventing contact of the dropping material with the burner flame, the nature of said means being such that the drier is adapted to dry loose material more rapidly than heretofore, and with less liability to deterioration or damage by the heat generated by the burner.

Of the accompanying drawings forming a part of this specification,—

Figure 1 is a side elevation of a drier embodying the invention, a portion of the elongated drum hereinafter described being broken away.

Figure 2 is a fragmentary perspective view, showing a portion of the inner drum hereinafter described.

Figure 3 is a section on line 3—3 of Figure 1.

Figure 4 is a section on line 4—4 of Figure 1.

The same reference characters indicate the same parts in all of the figures.

In the drawings, 12 designates an elongated open-ended drum, mounted to rotate on an inclined axis. In this instance, the drum

is supported by rollers, journaled in bearings on an inclined supporting frame 13, the drum being provided with peripheral grooved tracks bearing on the rollers. One 55 roller 14 and one track 15 are shown by Figure 1, and it is to be understood that the drum will be provided with two or more spaced apart tracks, and that each track bears on two rollers.

The drum may be rotated by a driving gear (not shown) meshing with a gear-toothed ring 16 surrounding the drum. At the higher end of the drum is a fixed head 17, covering said end and supporting a stack 18, and a chute 19, arranged to feed material into the higher end, the head, stack and chute being supported by a frame 20.

The drum 12 has a series of longitudinally extending inwardly projecting flanges 21, which I call distributing fells. These are adapted to alternately raise and release loose material fed into the drum by the chute 19, the fells extending from end to end of the drum. 22 designates somewhat conventionally, a fixed burner arranged to project flame into the lower end of the drum toward the higher end, the burner being supported by a fixed frame 23.

The structure thus far described is well known and is adapted to circulate loose material fed into the higher end of the drum and cause the material to progress in an approximately helical path from the higher to the lower end of the drum.

In carrying out my invention, I provide the improved means next described for additionally circulating and drying the material and preventing contact thereof with the burner flame, said means characterizing the invention.

25 designates an inner drum which is shorter and of smaller diameter than the longer drum 12, and is fixed to the longer drum within the lower end portion thereof. 95 The outer end of the drum 25 is substantially flush with the lower end of the drum 12.

The burner is preferably adapted to project a flame about four feet long, and the length of the inner drum 25 is such that it 100 surrounds the entire length of the flame.

Any suitable means may be employed to

secure the inner drum 25 to the lower end portion of the drum 12 in such manner as to maintain the drums substantially concentric with each other and separated by an annular space 26. In this instance I provide the inner drum with outwardly projecting arched brackets 27, whose outer ends are fixed to the fells 21 of the drum 12, preferably by angle strips 28, constituting extensions of the fells 21, as shown by Figure 4, each fell 21 being thus adapted to hold, raise and release a mass of loose material.

The inner drum is provided with a series of outwardly projecting distributing fells 29, each preferably of the channelled form shown by Figures 2 and 4, the fells 29 alternating with the fells 21, and being in staggered relation thereto. The annular space 26 contains the fells 29 and the end portions 20 of the fells 21. The arrangement is such that material distributed in the main portion of the drum 12 by the fells 21, enters the space 26, is distributed therein by the two series of fells, without contact with the burner flame, is acted on in all parts of said space by heat radiated from the inner drum, and is discharged from the outer end of the drum 12.

The drums are rotated in the direction of the arrow α , preferably about nine times per minute. Each fell portion 21 extended by the angular strips 28, raises material from the bottom of the space 26, and spills the material against the heated external surface of the inner drum. The gravitating material is caught by ascending fells 29, which in turn alternately raise and spill the material. It will be seen therefore that the circulating material moves in a zigzag, as well as a helical path in the space 26, and has a maximum exposure to heat radiated from the outer surface of the inner drum.

I have found by practical experience, that a drier characterized as above described, is capable of drying material much more rapidly than any other drier of which I am aware, because of the described peculiar circulation of the material in the space 26, and of the extended heat radiating surface provided by the inner drum. Moreover, I have found that the inner drum entirely surrounding the flame and rotating with the drum 12 is less liable to be warped and distorted by the heat of the burner flame than any other means known to me for preventing contact of the circulating material with the burner flame. The operative life of the drier is therefore increased and the delay and expense incidental to repairs are reduced.

To further increase the period of usefulness of the inner drum, I locate the burner eccentrically relative to the axis of the drums 12 and 25 (said drums being coaxial), so that one side portion of the inner drum is

nearer the burner flame and receives more heat therefrom than the opposite side portion. The rotation of the drums causes a continuous interchange of said drum portions, so that the more highly heated portions recede from the flame and part with a portion of their heat before again approaching the flame. Excessive heating of any portion of the inner drum is thus prevented, and the heat is effectively distributed in the space 75 26.

The inner drum may be provided at its outer end with an annular baffle flange 31, preferably of the tapering or flaring form shown by Figure 1, said flange partly closing 80 or obstructing the outer end of the annular space 26, and limiting the escape of dust from the said space, and particularly the upper portion thereof where the escape is naturally greatest.

The baffle flange deflects dust tending to escape from the upper portion of the space 26, and causes it to pass downward and be discharged from the drum 12 with the coarser dried material, so that the dust, or 90 the major portion thereof, is utilized as a part of the dried product.

I claim:

1. A device of the character stated, comprising an elongated open-ended drum, 95 mounted to rotate on an inclined axis, and having a series of longitudinally extending inwardly projecting distributing fells, adapted to alternately raise and release loose material fed into the higher end of the drum, 100 and a fixed burner arranged to project flame into the lower end of the drum toward the higher end, the drier being characterized by an inner drum which is shorter and of smaller diameter than the longer drum, and 105 is fixed to the longer drum within the lower end portion thereof, the inner drum having a series of longitudinally extending outwardly projecting distributing fells alternating with, and in staggered relation to the 110 inwardly projecting fells of the longer drum, the inner drum being proportioned and arranged to entirely surround and be heated by the flame projected by the burner, and separated from the lower end portion of the 115 longer drum by an annular space containing the inner drum fells and end portions of the longer drum fells, the arrangement being such that material distributed by the fells of the longer drum enters said space, 120 is distributed therein by the two series of fells, without contact with the burner flame, is acted on in all parts of said space by heat radiated from the inner drum, and is discharged from the outer end of the outer 125 drum.

2. A drier as stated by claim 1, the burner being eccentrically located relative to the axis of the drums, so that one side portion of the inner drum is nearer the burner 130

flame, and receives more heat than the opposite side portion, the rotation of the drums causing a continuous interchange of the said drum portions and preventing excessive heating of any portion of the inner drum.

3. A drier characterized as stated by claim 1, the inner drum being provided with outwardly projecting brackets, alternating with the outwardly projecting fells, and

fixed to the inwardly projecting fells of the longer drum.

4. A drier as stated by claim 1, the outer end of the inner drum being provided with an annular baffle flange, partly obstructing the outer end of the said annular space. 15

In testimony whereof I have affixed my signature.

WILLIAM H. DANCE.
